FUNCTION-MULTIPLYING DEVICE FOR AUTOMATIC MECHANISMS.

Application filed June 6, 1925. Serial No. 35,442.

The purpose of this invention is to provide a mechanism which may be operated by a controller, passing over a tracker or the like, for selectively controlling the action of a multiplicity of functioning devices, as in an automatic musical instrument or pattern loom; and the specific purpose is to provide means for the selective individual actuation of a major number of separate devices for 10 different functions by a minor number of actuators controlled by a minor number of control features in the controller sheet co-operating with a like number of motive fluid conductors in the tracker. It consists in the 15 elements and features of construction shown and described, as indicated in the claims.

In the drawings:

Figure 1 is a partial diagrammatic structure embodying this invention, electric and 20 pneumatic circuits or connections being indicated by mere lines for showing their course.

Figure 2 is a section at the line, 2-2, on Figure 3.

Figure 3 is a section at the line, 3-3, on 25 Figure 2.

Figures 4, 5 and 6 are elevations of the second, third and fourth of the combining plates or disks, the first plate being seen in Figure 2.

Figure 7 is a section similar to Figure 3, being a modification in which the combining plates have a double series of conductors for 30 making the combinations, section being made at such a plane as indicated at the line, 7-7, 35 on Figure 9.

Figure 8 is a diagrammatic view showing tracker duct and electric circuit connections for controlling a disk of the nature of an electric valve device to provide for adapting 40 the apparatus to control a plurality of functions to be performed concurrently, comprising a combining plate of the character employed in the modification shown in Figure 7.

Figure 9 is a diagrammatic view comprising 45 a plan view of one of the combining plates of the form shown in Figure 7, having a double series of conductors for the purpose of controlling two concurrently performed functions, the diagram indicating

the circuit connections to the several function-performing devices.

Figure 10 is a similar plan view of one of the combining plates having conductors for controlling three concurrently performed functions in the modification shown in Figure 7. 55

Figure 11 is a diagram for indicating in one plane the desirable and systematic distribution of the conductors in the several 60 combining plates.

In the drawings there is shown an embodiment of this invention for the purpose of enabling a limited number of pneumatic ducts of a tracker board co-operating with a like 65 number of lines of perforations of a perforated controller sheet to selectively control the operation individually of a much larger number of devices functioning in their several ways for the several partial and severable functions of the mechanism with which the tracker board is connected, which, in so far as they appear in detail in the drawings, are the devices for performing auxiliary functions in an automatic player 70 mechanism; but it will be understood that this mechanism is only selected for illustration, and that the invention is not limited to mechanism for any particular purpose, but is designed to be applied to any mechanism having parts to be selectively operated or controlled. 75

In these drawings (see Figure 1) there is shown a section of a tracker board, A, and of a note sheet, B, travelling across the tracker board for controlling the ducts of the former by the perforations of the latter. C¹, C², C³ and C⁴, are tubes leading from four ducts, c¹, c², c³ and c⁴, of the tracker to small pneumatics, d¹, d², d³ and d⁴, in a partial vacuum chamber, D, wherein these pneumatics operate electric switches, e¹, e², e³ and e⁴, for controlling electromagnetic devices, preferably duplex solenoids, E¹, E², E³ and E⁴, which for such control are connected by circuit wires, f¹, f², f³ and f⁴ with insulated contacts, g¹, g², g³ and g⁴, mounted on the chamber, D. 80

Each of the duplex solenoids, E¹, E², E³ and E⁴, is connected by a link, G, attached to 85 100

its reciprocating core member, E^{10} , E^{20} , E^{30} and E^{40} , to one of four disks, H^1 , H^2 , H^3 and H^4 , which constitute a group of combining plates which are mounted side by side for parallel movement between opposite side walls, K , K^1 , of a casing which may completely enclose these combining plates, and their respectively operating duplex solenoids, E^1 , E^2 , E^3 and E^4 .

10. These combining plates are actuated back and forth by the back-and-forth movement of the reciprocating core members, E^{10} , E^{20} , E^{30} , and E^{40} , of the respective duplex solenoids with which they are connected, the length of the step action being limited by a stop bar, I , fixed with respect to the member, H , on which all the combining plates, H^1 , H^2 , H^3 and H^4 , are mounted for their said parallel movements, said plates having each two stop lugs, h , shown in Figure 2, for stopping against said bar in the right-hand and left-hand movements respectively; and for preventing overflow in the return movement in either direction there are provided for each of the rotatable plates, H^1 , H^2 , H^3 , H^4 , a spring dog, W , engaging a notch, w , in the periphery of the plate. Each of said combining plates, being made of insulating material has a plurality of conductors extending through it arranged in succession along the path of its step movement, the extent of each combining plate in the path of its step movement being preferably a relatively large multiple of the diameter, or dimension in said path, of each of the conductors. In the embodiment of the invention which is shown in the drawings, these parallel-moving combining plates are disks mounted for rotation about a common axis, the path of movement, therefore, being circular about that axis, and the length of step movement being, in the particular construction illustrated, one-thirty-second of a full revolution, thus creating a possibility of thirty-two different conductors in the length of the path of movement. These conductors are each designated by a letter h with an exponent which is the ordinal of the conductor, counting in the right hand order from any selected starting point; that is to say, the conductor at the selected starting point being indicated by h^1 , the conductors in right hand order having their exponents increasing up to thirty-two; so that the last conductor to the right—one point to the left of the starting point,—is designated h^{32} . Conductors are not provided in all the combining plates, H^1 , H^2 , H^3 and H^4 , at all the step limits throughout the circuit or path of movement; but, on the contrary, each plate has certain blank or conductorless areas,—that is, certain step limits are without conductors, and these conductorless steps are distributed differently on the several combining plates, H^1 , H^2 , H^3 and H^4 . The

non-movable members, H and H^5 , between which all the conductor plates, H^1 , H^2 , H^3 and H^4 , are rotatably mounted have conductors in the form of insulated binding posts at all (except as hereinafter stated) of the thirty-two steps in the circle in which conductors of the combining plates are located. At only two points,—that is, at two of the step limits of the thirty-two (the points, 29 and 30, on Fig. 11), all four of the combining plates, H^1 , H^2 , H^3 and H^4 , have a conductor, so that there is registration of the positions of these conductors with each other through-and-through all four combining plates at the normal position of rest of said plates only at two points in the entire circumference; and at these two points the fixed member, H , may have the binding post conductors omitted; or if present,—as shown in dotted line in Fig. 1, which shows all thirty-two binding posts,—the binding posts at these two step limits are without circuit wire connections with any device to be operated, and are therefore functionless. For the purpose hereinafter described, the remaining thirty binding post conductors have circuit wires connected,—as seen in Figure 3 with respect to the two posts, h^9 and h^{25} which appear in that figure. These circuit wires are designated and may be referred to by reference letters, J and j , with exponents corresponding to those of the respective binding posts, those seen in Figure 3 being accordingly designated J^{25} and J^9 .

The distribution of the conductorless areas or points on the several combining plates, H^1 , H^2 , H^3 , and H^4 , is such that at the normal position of rest of said plates there is no through-and-through registration of operative conductors, and so that a one-step movement—which is all that is possible, of one of the plates away from that position of rest, will complete the through-and-through registration of the conductors at some one point; and movement of another of the plates one step will complete the registration at some other one point, the movement of a third plate one step will complete registration at a third point, and the movement of the fourth plate one step will complete registration at a fourth point; and so that the movement of the plates by twos will complete registration at as many different points as the number of possible combinations, two-and-two, of four units being six; and that the movement of the plates by threes, each one step, will complete the registration of all four plates at as many different points as the number of possible combinations by threes, which is four; and as above noted, all four plates having registered conductors at one point in the rest position of the plates, the movement of all four plates one step will bring these four registered conductors into registration with a binding post conductor

of the fixed member, H, thus completing registration through-and-through of conductors of all four plates and the binding post conductor of said fixed member.

- 5 Fifteen combinations or groups being possible of any four units (counting a single one as a group), it will be seen that it will be possible by simultaneously actuating either any one of the four plates, H¹, H², H³ and H⁴, or, any two of them, or, any three of them, or, all four of them, to thereby produce registration through-and-through for connection with any one of fifteen circuit wires, J, with an exponent which are connected with certain fifteen binding post conductors in the fixed member, H, whose ordinal is the exponent of J. It will also be noticed that the fifteen registrations indicated are effected by movement of the binding plate in one direction,—say, to the right. Another fifteen registrations may be effected similarly by moving the binding plates, H¹, H², H³ and H⁴, singly or in groups of two, three or four, to the left, thereby effecting 25 registration through-and-through with any one of fifteen additional binding post conductors of the fixed members, and with any one of the circuit wires, j with an exponent, which exponent is the ordinal of the binding post conductor. The circuit wires of the series, J and j with the exponent,—except one as hereinafter mentioned has leading to a duplex solenoid for a particular purpose,—may be understood as leading each to a magneto-pneumatic unit indicated conventionally at L (Fig. 1) which comprises an electro-magnet L² and a motor pneumatic, L², for performing any specific function required in the operation of the mechanism for which 35 the device is designed, and in the present instance for performing any one of the auxiliary functions in an automatic player mechanism or the like.
- By reference to Figure 11 in which the circles No. I, II, III and IV show the distribution of the conductors and the conductorless areas of the binding plates, H¹, H², H³ and H⁴, respectively, and the thirty-two numbered radial lines indicate the position 40 of the thirty-two possible out-leading conductors of the J and j series respectively, which are fifteen in each series, plus two conductorless points, it may be understood that the combining plates being given a single step movement to the right or to the left will thereby effect through-and-through registration of their conductors, and so open electric communication with the circuit wires 45 of the two series, J and j, for operating function-performing devices such as the motor pneumatic, L², of the magneto-pneumatic unit, L, for actuating whatever mechanism or part of a mechanism is served by the device. The following table shows this 50 distribution, and may also serve to show

whatever through-and-through registrations are possible, as may be ascertained from Figure 11.

110

115

For actuating the binding plates, H¹, H², H³ and H⁴, selectively either to the right or to the left, according to the particular functions to be immediately performed by the group of solenoids next to be brought into action, each of the solenoids, E¹, E², E³ and E⁴, is preferably of the duplex type,—that is to say, its reciprocating core is interposed between and extends into two fixed members having the solenoid windings, said core at rest position extending equally into both 120 125 130

windings, the two windings being connected with circuit wires of the series, J and j , respectively for energizing them to give the core member its operating stroke which will be in one direction or the other according to which of the windings is thus energized.

For controlling these duplex solenoids circuit wires, n^1 , n^2 , n^3 and n^4 , lead from the inner windings of the respective solenoids, E^1 , E^2 , E^3 and E^4 , to binding post conductors, x^1 , x^2 , x^3 and x^4 , in a conductor board, EE ; and from the outer windings of the respective solenoids, circuit wires, m^1 , m^2 , m^3 and m^4 , lead to binding post conductors, y^1 , y^2 , y^3 and y^4 , of the same conductor board, EE , the binding post conductors of the first set alternating with the binding post conductors of the second set in said board; and a switchboard, ee , is mounted upon the conductor board, EE , with range of movement to register the binding post conductors, ee^1 , ee^2 , ee^3 and ee^4 , either with the binding post conductors, x^1 , x^2 , x^3 and x^4 , or with the binding post conductors, y^1 , y^2 , y^3 and y^4 . The circuit wires, f^1 , f^2 , f^3 and f^4 , are connected respectively with the binding post conductors, ee^1 , ee^2 , ee^3 and ee^4 , of the switchboard, ee .

A duplex solenoid, L^x , controlled as to one of its windings by any selected circuit wires, J (with numeral exponent) and as to the other winding by the corresponding circuit wire, j , (with numeral exponent) has the reciprocating core member, L^{x1} , connected with the switchboard, ee , for actuating the latter in one direction for registering one set of conductors, and for actuating said board in the opposite direction for actuating the other set of conductors. The two circuit wires shown as selected being J^6 and j^{21} , are respectively rendered operative for bringing into service the solenoids which they respectively control by the same combining plate movements, which according to the foregoing table are of the combining plates, I, II and IV; only that in the case of the wire, J^6 , the movement is to the left, and in the case of the wire, j^{21} , the movement is to the right; but the group of apertures in a note sheet for moving the combining plates mentioned will always mean,—and always produce,—a reversal of the direction of the step movement of the plates, H^1 , H^2 , H^3 and H^4 . If the last preceding movement was to the right, the wire, J^6 , will be brought into the circuit and the valve board, ee , will be shifted so that the step action will be to the left; and if the last step action was to the left, the wire, j^{21} , will be brought into the circuit and will cause the valve board to be shifted in the opposite direction, causing the next step action to be to the right.

If in the mechanism in connection with which this device may be applied, certain functions to be performed are required to be

performed simultaneously with one, two, or even with three other functions, the present invention may be adapted to such simultaneous production of such simultaneous functions by means which will now be described. 70

At the side of the group of combining plates, H^1 , H^2 , H^3 and H^4 , opposite that at which the fixed member, H , is situated, there is mounted upon the common axis of said plates what may be called a valve member, H^5 ; and the several plates, H^1 , H^2 , H^3 and H^4 , which have conductors, h^1 to h^8 , to be registered through-and-through for any of the functions concurrently with which other functions are to be performed, are provided with conductors denoted by h^x , with a numeral exponent, said conductors radially aligned respectively with the conductors of the h series having the same numerical exponent as those of the outer circle with which they are thus radially aligned, said conductors, h^x , with an exponent, being arranged in a circle concentric with said principal or outer circle of conductors, h with a numeral exponent. This valve member, H^5 , has a normal position at which all its conductors are out of registration with the conductors of the inner circle of conductors of the series, h^x , and are brought into registration with them respectively upon movement of said valve member a certain step from its normal position of non-registration. An additional tracker duct c^x and line of controller sheet perforations b^x may be used for actuating the valve member, H^5 , by means of a magneto-pneumatic unit, M , comprising solenoid E^5 , corresponding to the solenoids, E^1 , E^2 , E^3 and E^4 the perforations in the line for controlling it being made to hold said valve member at the first described position throughout any portion of the travel of the note sheet through which simultaneous performance of two functions is desired, the valve member, H^5 , being preferably returned to closing position by a spring, M^1 , when the action of the magneto-pneumatic unit, M , ceases at the termination of the aperture (or group of closely successive apertures having the effect of a continuous aperture) in the control sheet which covers it. 100

When the total number of functions which it is desired to control is less than the number of combinations available which in the construction illustrated having the combining plates sub-divided for thirty-two steps is twenty-eight when only four original tracker ducts are utilized, one combination of each total of fifteen being used for changing the direction of step movement, the excess may be taken advantage of for two or more simultaneous functions dispensing with the valve member, H^5 , and with the use of the additional tracker duct for controlling it. This is done in the following manner: 110

Any particular function which is sometimes to be performed alone and sometimes to be performed simultaneously with another function has appropriated to it two combinations of a possible total of fifteen. For one of them the combining plates, H^1 , H^2 , H^3 and H^4 , and the fixed member, H , have conductors only in the outer or principal circle, and for the other function said members have additional conductors arranged in an inner or secondary circle; and circuit wires for controlling the second function lead from the binding post conductors of the fixed member, H , in the second circle for connection with circuit wires from the binding post conductors of the first circle which pertain to the second function. Four illustrations of this expedient are shown in Fig. 9 of the drawings. Radially aligned with the conductors, h^6 , h^{12} , h^{18} and h^{24} , of the principal circle, the second circle (see Fig. 9) in each of the combining plates, H^1 , H^2 , H^3 and H^4 , and the fixed member, H , has conductors, h^{x6} , h^{x12} , h^{x18} , h^{x24} , and the circuit wires, j^{x6} , j^{x12} , j^{x18} , j^{x24} , leading from these ports in the fixed member, H , are all connected with the circuit wire, J^9 , leading from the binding post conductor, h^9 . The binding post conductor, h^6 , h^{12} , h^{18} and h^{24} , may be understood as constituting a set of conductors, controlling for example, the selection of solo groups for accentuating the solo in playing, in case of the employment of this invention for controlling an automatic playing mechanism. Four other binding post conductors, for example, h^2 , h^8 , h^{14} and h^{20} , are also connected for controlling the same functions respectively, and the circuit wires, j^2 , j^8 , j^{14} and j^{20} , leading from the binding post conductors, h^2 , h^8 , h^{14} and h^{20} , are connected respectively with the circuit wires, j^6 , j^{12} , j^{18} and j^{24} , leading from the binding post conductors, h^6 , h^{12} , h^{18} and h^{24} , as seen at 40; so that either of the two combinations will perform respective solo functions. The binding post conductor, h^9 , may be assumed to be the controlling conductor for any function which is to be performed simultaneously with these solo functions, as, for example, for controlling the soft pedal for softening the accompaniment. When the solo functions are to be performed alone, the combination of controller sheet perforations for binding post conductors, h^2 , h^8 , h^{14} and h^{20} , will be used, and when the solo functions are to be performed simultaneously with the soft pedal functions, the combination for binding post conductors, h^6 , h^{12} , h^{18} and h^{24} will be used. It will be evident that a similar expedient may be employed for more than two functions; that is, a third circle of conductors may be used having conductors at certain radial lines where three through-and-through registrations will be obtained from the same combination of ap-

ertures in the controlling sheet. This is indicated by ports marked h^{y6} , h^{y12} , h^{y18} , h^{y24} , in Figure 10. The method of carrying out the circuit wire connections from these conductors of the third series may be understood from the foregoing descriptions as to the conductors from the second series without further illustration.

I claim:—

1. A device for the purpose indicated comprising a plurality of combining plates mounted for movement in parallelism with each other through definite step distances; means for positioning them all normally at a selected starting or rest position, and means for giving them individually in selected groups a definite step movement from said normal rest position, each plate having a series of electric current conductors arranged in succession along the path of the step movement, each plate having an interruption in the series of conductors at a point at which the other plates have the series uninterrupted, and having a conductor at the next step-distant point from that at which said interruption occurs; the several plates differing from each other as to the point at which the interruption occurs; whereby movement of different plates a step distance from the normal rest positions produces through-and-through registration of the current conductors in all the plates at different points in the path of movement.

2. In the construction defined in claim 1, foregoing, a fixed member adjacent to one side of the group of plates which have the step movement, said fixed member having motive fluid current conductors and current carriers leading therefrom at the step intervals along the path of movement of the plate, for registration with the through-and-through conductors of the movable plates.

3. In the construction defined in claim 1, each of the movable plates having two or more parallel series of conductors, the conductors of each series being arranged as called for in claim 1; whereby the same step movement of the same plate or combination of plates may effect registration through and through them at certain points simultaneously in each of the several series.

4. In the construction defined in claim 1, the means of step actuation of the conductor-carrying plates being adapted for moving them in either direction from the normal rest position, and means for shifting the connection of said operating means to change the direction of the step movement.

5. In the construction defined in claim 1, the means of step actuation of the conductor-carrying plates being adapted for moving them in either direction from normal rest position, and said means having alternative connections with a source of electric current causing said means to operate for move-

ment in one direction or the other according to the alternative made operative; and means for shifting the connection of said actuating means to change the direction of 5 the step-by-step movement, said last mentioned means comprising electric circuit connections from one line of through-and-through registered conductors whose registration is produced by means of a selected 10 combination of the movable members.

6. A device for the purpose indicated comprising in combination, a perforated controller sheet and a tracker having ducts co-operating with the perforations of the sheet; 15 a partial-vacuum chamber and primary pneumatics therein duct-connected with the tracker ducts respectively; motive-fluid-operated means controlled by the primary pneumatics respectively, and movement- 20 communicating connections therefrom, a group of combining plates mounted for movement in parallelism with each other through a definite step distance; means for positioning all said plates normally at a 25 selected starting or rest position; said movement-communicating connections being connected to said combining plates respectively for giving the plates individually in selected groups, definite single step movements from 30 said normal rest position, each combining plate having a series of electrical conductors each extending through the plate from side to side arranged in succession along the path of step movement of the plate, each 35 plate having an interruption in the series of electrical conductors at a point at which the other plates of the group have the series uninterrupted, and having one of the conductors at the next step-distant point from 40 that at which said interruption occurs, the several plates differing from each other as to the point at which the interruption occurs; whereby, upon movement of different

plates a step distance from their respective normal rest positions, through-and-through 45 electrical connection from the outer side of the extreme plate at one side of the group to the opposite outer side of the other extreme plate occurs at different points in the path of movement; electrically operated 50 means for controlling function performing devices, and means for completing electric circuits comprising the registered conductors of the combining plates and said means. 55 7. In the construction defined in claim 6, the means controlled by the primary pneumatics being electro magnetic devices having their moving armature elements connected with the respective combining plates. 60 8. In the construction defined in claim 6, the electrically-operated function-controlling means being electro-magnetic devices and valve-controlled motor pneumatics 65 constituting the function-performing means; and valves for controlling said pneumatics operatively connected with the armature elements of said electro-magnetic devices.

9. In combination with the construction defined in claim 6, fixed members at opposite sides of the group of combining plates, said 70 fixed members having insulated binding post conductors at the step intervals along the path of movement of the conductors of the combining plates for registration and electrical connection through the group of 75 plates, and electric circuit wires for completing electric circuits through said registered binding posts and combining-plate-carried conductors and the electrically-operated controllers for the function-performing 80 devices.

In testimony whereof, I have hereunto set my hand at Chicago, Illinois, this 1st day of June, 1925.

CHARLES S. BURTON.
